UNITED STATES PATENT OFFICE.

SIMON CLARY, OF CARNEGIE, PENNSYLVANIA.

GUARD DEVICE FOR RAILWAYS.

1,353,723.

Specification of Letters Patent. Patented Sept. 21, 1920.

Application filed January 17, 1920. Serial No. 352,061.

To all whom it may concern:

Be it known that I, SIMON CLARY, a citizen of the United States, residing at Carnegie, Allegheny county, Pennsylvania, have 5 invented a new and useful Improvement in Guard Devices for Railways, of which the following is a full, clear, and exact description.

The present invention relates broadly to 10 safety devices for railways, and more particularly to a guard device adapted to be used in connection with track frogs and switches to insure the proper travel of car wheels thereover.

15 The principal object of the present invention is to provide a device adapted to coöperate with certain of the rails to produce lateral movement of the car wheels traveling thereover to prevent "splitting" of 20 switch points or the like.

Another object of the invention is to provide means of the character referred to which may be used on high-speed tracks for producing a gradual lateral movement 25 of the wheels.

Still another object of the invention is to provide a guard device of this character arranged to rotate freely under impact with a wheel to thereby eliminate excessive strain 30 and friction.

An additional object of the invention is to provide a guard device constructed to minimize the possibility of accident to people working on rails or tracks so equipped.

35 A further object of the invention is to provide a rotatable device of the nature described which has its upper surface lying substantially in the plane of the tread of the rails.

40 A still further object of the present invention is to provide a removable rotating element or wheel-engaging member, thereby permitting substitution or replacement thereof, as desirable.

45 The foregoing and other objects, together with their attendant advantages, will be apparent as the invention becomes better understood by reference to the accompanying specification and drawings forming a part 50 thereof, it being premised that changes may be made in the various details and the manner of operation within the scope of the appended claims without departing from the spirit of the invention.

55 Figure 1 is a view, largely diagrammatic,

of a track layout having my improved guard device applied thereto.

Fig. 2 is an enlarged plan view of the device.

Fig. 3 is a sectional view through the device, the wheel-engaging element being shown in elevation.

Fig. 4 is a sectional view between the upper and lower plates, and

Fig. 5 is a detail perspective view of one of the guard plates.

The present invention relates particularly to guard devices which may be applied adjacent switch points or frogs to insure a sufficient lateral movement of the car wheels

traveling on the rails equipped with the device to prevent splitting of the switch points or frogs. With tracks as ordinarily constructed there is danger when running toward the points or frogs to split the same,

70 due to the fact that the wheels are not in the proper position for continuing their travel either on the through tracks or for switching onto the side tracks. This danger of course does not exist in tracks where

75 the movement of the cars thereover is such as to trail the switch points, but it is seldom travel is limited in this respect.

Referring more particularly to the drawings, I have illustrated a through track comprising the rails 2 and a side track comprising the rails 4, the usual switch points

5 and frog 6 being employed in this layout. For insuring the wheels of a car trav-

eling in the direction of the arrow A of 80 Fig. 1 taking the switch in the proper manner, there is provided adjacent one of the tracks a series of guard devices 7. Each of these devices in its preferred embodiment

comprises a supporting member cast or 85 otherwise formed to provide upper and lower plates 9 connected by a boss 10 and reinforcing ribs or flanges 11. The boss 10

is formed to provide a bearing for the stem 12 of a wheel engaging element 14. In the 90 present form this element is illustrated as comprising an enlarged head formed on the stem 12 and rotatably mounted in the depression 15 formed in the upper plate 9. The

lower plate is preferably of such width that 95 it may have its opposite edges secured to adjacent ties, spike openings 16 being provided for this purpose. One end of the base mem-

ber also preferably extends under the rail to form a chair therefor, the top plate be-

100

120

ing cut away, as indicated at 17, to permit the same to be readily passed under the head of the rail. It is desirable that the parts be so proportioned that the upper surface of the wheel engaging element 14 and the top plate 9 lie in the plane of the tread of the rail. The stem 12 may be extended below the lower plate and provided with a suitable fastening means, here illustrated as 10 comprising a nut 18.

Where a single guard device of the nature described is employed, it will be so secured in position with respect to the rail that the periphery of the wheel-engaging element 14 15 will be sufficiently close to the rail to engage the flange of a wheel passing thereover and move the same in a lateral direction. This movement will be sufficient to insure the wheels taking the switch in the proper 20 manner.

For high-speed tracks, however, it is desirable that a series of such devices be employed, and the devices on opposite sides of the central device located at gradually increasing 25 distances from the tread of the rail. With such a construction a wheel flange will be successively engaged by the devices and gradually moved laterally to the required position. This arrangement is 30 illustrated particularly in Fig. 1, in which figure there is shown a series of three guard devices for both switch points 5 and the frog 6, the central device in each instance being located slightly in advance of the 35 point or frog which it protects. The guard devices employed on opposite sides of the center device differ therefrom only in the location of the boss 10, this boss in such devices being positioned slightly farther from 40 the rail engaging portion of the top plate than in the center device. Due to this arrangement the desired movement of the wheels is insured. It is desirable to have guard devices in most instances located on 45 opposite sides of the center device in order to protect the center device when the wheels are either traveling toward or trailing the switch point or frog.

Where a series of devices are employed, it 50 is also desirable to provide supplementary guard plates, such as illustrated more particularly in Fig. 5, each comprising a main body portion 19 and a downwardly and forwardly extending portion 20 adapted to 55 underlie the head of the rail intermediate adjacent guard devices. The edges of the main body portion may be provided with openings 21 spaced to conform with the openings 22 formed in each of the guard devices 60 adjacent the countersunk edges 24 thereof to receive bolts or other fastening means. The guard plates constitute substantial continuations of the guard devices thereby providing a smooth upper surface. 65 Under the impact of a car wheel, the

wheel engaging elements 14 will be slightly rotated so that strain and excessive friction are eliminated. With such a construction also the wheel-engaging elements are removable at will to permit substitution or replacement, as found desirable. 70

The advantages of the present invention arise from a construction in which both strain and friction are to a large extent eliminated and in which the movement of 75 the wheels laterally is accomplished in successive stages.

I claim:

1. A guard device for rails, comprising a supporting member adapted to coöperate 80 with a rail, a bearing therein, and a wheel-engaging element mounted to rotate in said bearing about a fixed vertical axis, substantially as described.

2. A guard device for rails, comprising a supporting member adapted to coöperate 85 with a rail, a bearing therein, and a wheel-engaging element rotatably mounted in said bearing, said element and said member having their upper surfaces lying in substantially 90 the plane of the tread of the rail, substantially as described.

3. A guard device for rails, comprising a supporting member adapted to coöperate 95 with a rail and provided with means for securing the same to a tie, a bearing therein, and a horizontally extending wheel-engaging element rotatably mounted about a vertical axis in said bearing, substantially as described. 100

4. A guard device for rails, comprising a supporting member adapted to coöperate with a rail, a bearing therein, and a wheel-engaging element rotatably mounted in said bearing, said element comprising a stem having an enlarged wheel-engaging head, substantially as described. 105

5. A guard device for rails, comprising a supporting member formed with upper and lower plates, said upper plate having a depression therein, a bearing in said member, and a wheel-engaging element in said bearing and rotatable in said depression, substantially as described. 110

6. A guard device for rails, comprising a 115 supporting member adapted to coöperate with a rail, said member having a depression formed in its upper surface, a wheel-engaging element rotatably mounted in said depression, the upper surface of said element lying substantially flush with the upper surface of said member, and means for holding said element in position therein, substantially as described. 120

7. A guard device, comprising a wheel-engaging element secured adjacent a rail tread for rotation about a fixed vertical axis, and a similar element located at one side thereof and coöperating therewith, substantially as described. 125

8. A guard device, comprising a wheel-engaging element secured adjacent a rail tread for rotation about a fixed vertical axis, and a similar element located on opposite sides thereof and coöperating therewith, substantially as described. 5
9. A guard device, comprising a wheel-engaging element secured adjacent a rail tread, and a similar element located at one side thereof and coöperating therewith, said second element being spaced a greater distance from the rail tread than the first element, substantially as described. 10
10. A guard device, comprising a center wheel-engaging element secured adjacent a rail tread, and similar elements located on opposite sides thereof, said second elements 15

being spaced a greater distance from the rail tread than the first element, substantially as described. 20

11. A guard device, comprising a series of supporting members, a wheel-engaging element carried by each of said members, and guard plates intermediate said elements, substantially as described. 25

12. A guard device, comprising a series of supporting members, a rotatable wheel-engaging element carried by each of said members, and guard plates intermediate said elements, substantially as described. 30

In testimony whereof I have hereunto set my hand.

SIMON CLARY.
